UNITED STATES PATENT OFFICE.

JOHN E. HILL, OF CENTER HARBOR, NEW HAMPSHIRE, ASSIGNOR TO
THE J. E. HILL COMPANY, OF BOSTON, MASSACHUSETTS, A COR-
PORATION OF MASSACHUSETTS.

EGG-BEATER.

No. 841,320.

Specification of Letters Patent.

Patented Jan. 15, 1907.

Application filed July 13, 1906. Serial No. 326,094.

To all whom it may concern:

Be it known that I, JOHN E. HILL, a citizen of the United States, and a resident of Center Harbor, county of Belknap, and State 5 of New Hampshire, have invented an Improvement in Egg-Beaters, of which the following description, in connection with the accompanying drawings, is a specification, like numerals on the drawings representing 10 like parts.

This invention relates to egg-beaters, and has for its object to provide a novel egg-beater which is simple and inexpensive to manufacture and which may be readily 15 taken apart for cleaning.

In all rotary egg-beaters with which I am familiar the rotary beating members are fixedly secured in the frame and cannot be removed therefrom for cleaning or other purposes. The result is that it is often quite a 20 task to properly clean the egg-beater after it has been in use.

In my improved egg-beater I have so mounted the beating members that they can 25 be readily removed from the frame, and thus easily washed and dried. I propose, also, to make the frame of my egg-beater of suitable wire which is bent to shape, this making a very inexpensive but practical and suitable 30 frame.

In the drawings, in which one simple embodiment of my invention is illustrated, Figure 1 is a view of the egg-beater. Fig. 2 is a section on the line *xx*, Fig. 1. Fig. 3 is a view 35 of the frame. Fig. 4 is a section on the line *yy*, Fig. 1; and Fig. 5 is a section on the line *aa*.

The frame is designated by 3 and is preferably made from suitable wire which is bent 40 to the proper shape, and it comprises a handle portion 19 and a loop portion 16, within which loop portion the beating elements rotate. The handle and the loop portion are made rigid with each other, are non-detachable from each other, and preferably are made as an integral structure. In this embodiment of my invention there are two rotary beating members, (designated 4 and 5, respectively.) The beating member 5 comprises a spindle or shaft 6, having at its lower end blades or arms 7 and having fast thereto at its upper end a pinion 8. The lower end

of the spindle 6 is journaled in a socket 9, formed in the frame, and its upper end is journaled in the bridge-piece 10, also carried by the frame. The other beating member 4 is rotatably mounted on the spindle 6 and has a general loop shape and may be made from either round or flat wire. At its upper end it has rigid therewith a pinion 11, which rotates on the spindle 6, and at its lower end it is journaled on the lower end of the spindle 6, as at 12.

The pinions 8 and 11 are driven in opposite directions by means of a driving-gear 13, 65 which is herein shown as journaled on a stud 14, carried by a support 15. The frame 3 has the general shape shown in Fig. 3—that is, it has at its lower end the loop portion 16, within which the beating members rotate. 70 At its central portion it is narrowed in, as at 17, where the support 15 is sustained. It is widened again at 18, where the bridge 10 is sustained, and the upper end thereof is bent to form the handle 19. This handle 19 has 75 an inwardly-extending tongue or member 20, the end of which normally stands directly over the upper end of the spindle 6, as shown in Figs. 1 and 2, and holds the spindle against vertical movement.

It will be noted that the two beating members 4 and 5 rotate in opposite directions, and therefore operate to beat the material very rapidly. Furthermore, the two pinions 8 and 11 are situated on opposite sides of 85 the driving-gear 13, and therefore the pressure on the driving-gear is always completely balanced and there is no tendency for the pinions to be thrown out of mesh with the driving-gear.

The tongue 20 of the handle is made of resilient material, so that it may be forced to one side, as shown in dotted lines, Fig. 2, and when in this position the spindle 6 may be elevated sufficiently to withdraw the lower 95 end thereof from the socket 9, when by swinging the lower end outwardly, as shown in dotted lines, Fig. 2, said spindle may be entirely removed from the frame.

The driving-gear 13 may also be detached 100 from the frame. Referring to Fig. 4, it will be seen that the support 15 is provided with the curved arms 180, which embrace the sides of the frame 3. The frame is made re-

silent, so that these sides may be sprung inwardly sufficiently to allow the support 15 to be removed therefrom.

The bridge 10 is preferably provided with 5 the notches or recesses 20 in its ends, in which the bent portions 18 of the frame 3 are received, and said bridge may be permanently secured to the frame by solder or otherwise or may be securely held in place by the resiliency of the frame.

From the above it will be seen that the egg-beater is very simple to make, and it may be readily taken apart for cleaning or repairing.

The drawings show one embodiment of the 15 invention only.

Having fully described my invention, what I claim as new, and desire to secure by Letters Patent, is—

1. In an egg-beater, a frame comprising a 20 handle and a loop portion made as an integral structure, a rotary beating member detachably supported by the frame, and means to rotate said member.

2. In an egg-beater, a frame comprising a 25 handle and a loop portion made as an integral structure, a rotary beating member supported by the frame, and means to rotate said member, said rotating means and said beating member both being removable from 30 the frame.

3. In an egg-beater, a frame, two rotary 35 beating members both rotatable about the same axis and detachably carried by the frame, and means to rotate said beating members.

4. In an egg-beater, a frame, two rotary beating members both rotatable about the

same axis and detachably carried by the frame, and means to rotate said beating members, said rotating means also being removable from the frame. 40

5. In an egg-beater, a frame, a bridge-piece carried thereby, and a beating member having a spindle, one end of which is journaled in the frame, and the other end of which is 45 journaled in the bridge-piece, said frame having a resilient portion to engage normally the end of the spindle and prevent longitudinal movement thereof.

6. In an egg-beater, a frame made from a 50 piece of wire bent to shape, a bridge sustained by said wire, and a beating member having a spindle, one end of which is journaled in the frame, and the other end of which is journaled in the bridge, said frame having a 55 resilient portion standing normally adjacent the bridge to limit longitudinal movement of the beating member, whereby when said portion of the frame is thrown into abnormal position the beating member may be removed. 60

7. In an egg-beater, a frame made of wire bent to shape, a rotary beating member supported thereby, a driving-gear for rotating said beating member, and a support for the driving-gear, said support having curved 65 arms to embrace the sides of the frame, but being detachable therefrom.

In testimony whereof I have signed my name to this specification in the presence of two subscribing witnesses.

JOHN E. HILL.
